CLAIM

The ornamental design for a vending machine, as shown and described.

DESCRIPTION

FIG. 1 is a perspective view of a first embodiment of a vending machine showing our new design;

FIG. 2 is a front view of the first embodiment of the vending machine shown in FIG. 1;

FIG. 3 is a rear view of the first embodiment of the vending machine shown in FIG. 1;

FIG. 4 is a right side view of the first embodiment of the vending machine shown in FIG. 1;

FIG. 5 is a left side view of the first embodiment of the vending machine shown in FIG. 1;

FIG. 6 is a top view of the first embodiment of the vending machine shown in FIG. 1;

FIG. 7 is a bottom view of the first embodiment of the vending machine shown in FIG. 1;

FIG. 8 is a perspective view of a second embodiment of a vending machine showing our new design;

FIG. 9 is a front view of the second embodiment of the vending machine shown in FIG. 8;

FIG. 10 is a rear view of the second embodiment of the vending machine shown in FIG. 8;

FIG. 11 is a right side view of the second embodiment of the vending machine shown in FIG. 8;

FIG. 12 is a left side view of the second embodiment of the vending machine shown in FIG. 8;

FIG. 13 is a top view of the second embodiment of the vending machine shown in FIG. 8; and,

FIG. 14 is a bottom view of the second embodiment of the vending machine shown in FIG. 8.

In the drawings, the broken lines illustrate environment and form no part of the claimed design.

1 Claim, 10 Drawing Sheets
